GLASS SEVERING APPARATUS

Stuart M. Dockerty, Pawtucket, R. I., David E. Gray and John W. Romig, Corning, N. Y., and William R. Wisner, Pawtucket, R. I., assignors to Corning Glass Works, Corning, N. Y., a corporation of New York

Application June 1, 1943, Serial No. 489,292

9 Claims. (Cl. 49—50)

1

The present invention relates to glass cane and tube severing equipment and particularly to equipment for receiving tubing as it comes from a forming machine and for disposing of the tubing or cane by breaking it into lengths convenient for shipment and use by the trade.

In the past it has been the general practice to employ equipment carried back and forth along the tubing or cane by the drawing apparatus to sever the tubing or cane into sections of a desired length. One form of severing equipment commonly employed is a moistened scoring tool which effects the severance by its combined scoring action and thermal shock to the tubing while still hot from the forming operation.

The foregoing and similar forms of severing equipment heretofore employed have lacked in facilities to readily modify the severed lengths as required to meet different uses. Also the heretofore used methods of effecting fracture have been very inexact. For example, when severance is effected in the specific manner above described, only a minor portion of the tube surface is scored and, as there is no definitely established pattern for the initial break to follow, the break is usually irregular and often extends for some distance lengthwise of the tube before severance is fully effected. This necessitates arranging the equipment to break the tubing into greater lengths to produce desired tube sections of a desired minimum length than would be necessary if clean transverse breaks were made.

The present invention embodies equipment for locally heating the tubing at desired spaced intervals along narrow circumferential paths where the same is to be severed and means for then effecting severance by thermal shock by passive engagement of the locally heated tubing portion with a relatively cold element for ample time to effect fracture. The equipment for locally heating the tubing is carried back and forth along the tubing itself and includes facilities for very readily modifying the distance or frequency of back and forth travel to vary the distance between locally heated areas in accordance with the lengths of tubing desired.

In the accompanying drawings Fig. 1 is a plan view of a preferred form of machine embodying the invention;

Fig. 2 is a side elevation of the same, with certain parts broken away;

Fig. 3 is an enlarged view of a fragment of the machine taken on line 3—3 of Fig. 2 and with certain parts broken away;

Fig. 4 is a view taken on line 4—4 of Fig. 3 with parts shown in section;

2

Fig. 5 is a view taken on line 5—5 of Fig. 3 with certain parts broken away;

Fig. 6 is an end view of a fragment of the machine as seen when looking in the direction indicated by arrows 6—6 of Fig. 2;

Figs. 7 and 8 are plan and side elevational views of a modified form of the invention;

Figs. 9 and 10 show structural details of the modified structure;

Fig. 11 is a view taken on line 11—11 of Fig. 8; and

Fig. 12 is a side elevational view of a further form of the invention.

General description

15 In the embodiment of the invention illustrated in Figs. 1—6 the tubing or cane 11, for convenience hereinafter referred to only as tubing, is heated at desired spaced intervals by a ring burner 30 (Figs. 2, 3, and 5) which surrounds and moves with the tubing 11 a predetermined distance during travel of the tubing towards a delivery position, the distance of travel of the burner 30 depending upon the length of the sections desired. 20 During the continued advance of the tubing 11, the burner 30 is quickly returned to its initial starting point. In the meantime, the locally heated portion of the tubing travels under an internally chilled iron 50 (Figs. 1, 2, and 6) 25 which imparts the necessary thermal shock to the tubing to effect its severance. As will be fully brought out later, the burner 30 is supported on a carriage moved toward the delivery position by the tubing itself whenever a pair of chuck jaws 28 (Fig. 4) engage the tubing, and the carriage is returned to its starting point by means of a cable 31 (Figs. 1 and 2) wound about a pulley 32 by a turning force imparted to the pulley 32 through a wheel 33 driven by frictional engagement of its rim with the tubing 11. 30

Detailed structure

Referring again to Figs. 1—6 of the drawings, the severing equipment includes a frame 10 through which the tubing 11, issuing from a continuous drawing machine, in part shown in Fig. 12, passes over sheaves 16 and 17 (Figs. 2 and 6) supported on axles 18 and 19. The frame 10 also supports a pair of carriage rails 12 adapted to receive the supporting wheels 13 of a burner carriage comprising axles 14, wheels 13 and axle bridging bars 15. Intermediate their ends, bars 15 have attached thereto a roller race 21 (Figs. 2, 3, and 5) within which are confined three rollers 22 carried by a plate 23 (Figs. 3 and 4) of a tube chuck assembly. This assembly in-

cludes a pair of pneumatic units, each comprising a cylinder 25 containing a pneumatically operable piston 26 attached to one end of a rod 27. The other end of rod 27 carries a tube chuck jaw 28. A spring 29 normally holds the chuck jaw 28 from engagement with the tubing 11 which passes between jaws 28. Jaws 28 are brought into seizing relation with the tubing by supplying air to cylinders 25, as will be fully brought out hereinafter. The reason for supporting chuck jaws 28 and plate 23 through rollers 22 and race 21 is that ordinarily the tubing being drawn is turning slowly about its axial center and accordingly the chuck jaws must be able to turn with the tubing to prevent tube 15 breakage.

On the side of race 21 opposite that occupied by the chuck assembly is the ring burner 30 arranged coaxial with tubing 11. As indicated by the arrow in Fig. 2, the tubing is traveling to the right and it will be evident therefore that by moving chuck jaws 28 into seizing relation with the tubing 11 the carriage will move therewith and burner 30 will remain in a fixed position relative to the tubing to heat it at a desired severing point during the travel of the burner with the tubing. Return of the carriage assembly to its starting point is effected by means of cable 31 which winds about pulley 32 as it is turned in a counter-clockwise direction by the drive wheel 33 while it rests on and is driven by the tubing 11. Wheel 33 is carried in a frame 34 pivoted at 35 and has a pneumatic unit 36 coupled thereto through a depending portion 34' of frame 34 for turning the frame about pivot 35 as required to raise wheel 33 out of driving relation with the tubing 11 while the carriage is moving with the tubing. While the carriage is moving with the tubing 11 wheel 33 is held clear of the tubing and accordingly is free to turn as the cable unwinds from the pulley 32.

The supply of operating air to chuck cylinders 25 and pneumatic unit 36 is through a control valve 41 which is arranged to feed air to the lower end of unit 36 via a pipe 39 and to cylinders 25 via pipe 40 and a flexible tube 40' upon actuation of a bleeder valve 42 and to feed air to the upper end of unit 36 via a pipe 43 and connect cylinders 25 to atmosphere upon actuation of a bleeder valve 43. Valves 41, 42 and 43 are of conventional form, similar to valves disclosed in Goodrich Patent 2,267,236, granted Dec. 23, 1941. Valve 41 comprises a cylinder having a valving piston therein moved back and forth under control of bleeder valves 42 and 43 connected to its opposite ends. Air is constantly supplied to the respective ends of the cylinder from the air supply line via bleeder ports in its valving piston so that a balanced pressure exists at the cylinder ends so long as the connected bleeder valves remain closed and, accordingly, the piston remains in the position it has last moved. However, when such balance of pressure is destroyed by the opening of one of the bleeder valves, the piston shifts to the end of the cylinder which has been bled and remains in such position even after the bleeder valve is closed and a balanced pressure condition re-established. The shifting of the piston to the opposite end of the cylinder is similarly effected by actuation of the bleeder valve connected with the opposite end of the control valve. Bleeder valves 42 and 43 are slidably fixed to bars 44 secured to the top of frame 10 and accordingly their air supply lines 37 and 38 contain lengths of flexible tubing 37' and

38' to enable ready shifting of valves 42 and 43 as required to obtain severed sections of tubing of a desired length. Operation of the bleeder valves 42 and 43 is by means of a cam 45 (Figs. 1, 2, and 5) mounted on straps 46 bridging two arched supports 47 spanning wheel axles 14.

Extending beyond the delivery end of frame 10 is the chilling iron or shoe 50 (Figs. 1, 2, and 6) which is carried on the free end of an arm 51 pivoted to frame 10. The chilling iron 50 simply rests by gravity on the tubing 11 and, when a locally heated tube portion passes under it, imparts the necessary thermal shock thereto to effect severance. Shoe 50 is hollow throughout its length and has two connecting tubes 52 and 53 through which a suitable chilling fluid is circulated through the iron, thus giving it high heat absorbing capacity.

Operation

In Figs. 1 and 2 of the drawings the carriage assembly is shown just completing its return movement with control valve 41 supplying air to the upper end of unit 36 so that wheel 33 is resting on tubing 11 and therefore functioning to pull the carriage to the left, while cam 45 is just starting to actuate bleeder valve 42. As the movement is completed, bleeder valve 42 causes control valve 41 to shift and supply air to the lower end of unit 36 and to the cylinders 25. Unit 36 accordingly raises the wheel 33 to stop the return drive of the carriage assembly while the chuck jaws 28 move into engagement with tubing 11. The carriage assembly is accordingly moved to the right until its reverse movement is effected by cam 45 operating bleeder valve 43 which causes control valve 41 to change position which in turn causes wheel 33 to be lowered into engagement with tubing 11 and also permits spring 29 to disengage chuck jaws 28. As already explained, the tubing is severed at the points heated as it passes under iron 50.

In the form of the invention illustrated in Figs. 7-10 a chain 55 suspended between the left end of frame 10 and the left end of carriage 15 by its own weight provides the energy to return the carriage to the left end of frame 10 when chuck jaws 28 are released. The air supply to chuck cylinders 25 is through valves 62, an air line 66, valve 63 and an air line 67. Valve 62 is opened by a lever 65 adapted to be actuated jointly by a spring 62' and by tubing 11 passing thereunder and effecting a lifting of the lever through its associated roller. Valve 63, and a similar valve 64 adapted to exhaust the cylinders 25 to atmosphere via lines 67 and 67', are adapted to be opened alternately by a valve actuator 60. Actuator 60 is operated by a carriage carried cam 57 at the final stage of leftward movement of the carriage to permit valve 64 to close and to open valve 63 at which time valve 62 is being held open. The chuck jaws 28 are accordingly actuated to seize the tubing 11 so that the carriage is moved to the right, as illustrated in the drawing. During the final portion of movement to the right cam 56 engages and operates valve actuator 60 to permit the closure of valve 63 and to open exhaust valve 64. The chuck jaws 28 accordingly become released from engagement with the tubing 11 and the carriage is quickly moved to the left under the influence of chain 55. In the meantime the heated section of tubing 11 passes under iron 50 which effects fracture of the tubing which drops away from roller carried by lever 65 permitting valve 62 to close. Move-

ment of the carriage to the left is halted by its engagement of a spring loaded roller or stop 61 just after cam 57 has passed under valve actuator 60 to prepare for the next rightward movement of the carriage 15. As soon as valve 62 is again actuated by the end of the tubing 11 passing under the roller of lever 65 chuck cylinders 25 again receive air and accordingly jaws 28 again seize tubing 11 to move the carriage to the right.

As will be observed, the support 58 for valve 62 may be readily shifted to modify the distance of valve 62 and its actuator lever 65 from frame 10 to regulate the length of tubing being severed by loosening cap screw 58', sliding the support to the right or left as desired and retightening the cap screw. Also the position of carriage stop 61 may be readily changed to modify the leftward limit of travel of the carriage exactly as desired by loosening cap screw 61', sliding the stop 61 to the left or right as desired and retightening the cap screw.

In the form of the invention illustrated in Fig. 12 the supply of operating air to chuck cylinders 25 is through a spring closed solenoid valve 75 and the connection of the chuck cylinders to atmosphere is through cam actuated exhaust valve 76. Valve 76 is arranged on the bars 44, which in Figs. 1 and 2 support similar valves, and is adapted to be held open by a cam 77 during the latter portion of the rightward travel of carriage 15. The solenoid valve 75 is operated by current supplied through contact springs 78 actuated by a cam 79 adapted to hold the springs closed during one third of a cycle during which time valve 75 supplies air to chuck cylinders 25 to enable jaws 28 to seize the tubing 11 and thus move the carriage 15 to the right. The drive of cam 79 is taken off the tube drawing drive mechanism 80 through a variable speed transmission 81. As shown in the drawing the carriage 15 is moving to the right. Some time before cam 77 encounters and actuates exhaust valve 76 cam 79 permits springs 78 to open the circuit of solenoid valve 75, permitting this valve to close. Therefore when valve 76 is subsequently opened the cylinders 25 are exhausted to atmosphere thus permitting the carriage 15 to move leftward under the influence of chain 55. The time of commencement of the movement of the carriage 15 to the right depends upon the turning speed of cam 79. The lengths of the tubing being cut can accordingly be adjusted at will through the medium of the variable speed transmission 81 by the simple expedient of changing the turning speed of cam 79 relative to the tube drawing speed. On the other hand, since the cam 79 is driven off the tube drawing drive 80 the lengths of sections remain constant for a given variable speed transmission setting irrespective of the drawing speeds.

In order to guard against the chilling iron 50 swinging down into the path of on-coming tubing, should the same inadvertently be broken before passing under the iron, it is advisable to arrange a stop under the swinging arm 51. This safety feature has been shown in Figs. 7, 8, and 11 and comprises a bracket 82 attached to frame 10 and having an adjustable stop screw 83 for engagement by arm 51.

As will be appreciated, in all forms of the invention, the burner 30 heats a very narrow circumferential band of glass while traveling with the tubing thus assuring that when a thermal shock is imparted to the heated portion a clean break transverse of the tubing will be made. Also the surface of iron 50 engaged by the tubing is

perfectly smooth and accordingly abrasive action which may be the cause of the initiation of breaks lengthwise of the tube is entirely avoided. Furthermore, owing to the substantial length of iron 50 compared to the very narrow heated band encountering it and the further usual turning movement of the tubing about its own axial center while passing under iron 50, the application of the thermal shock occurs progressively along a portion of the length of the circumferential band and is thus continued for an ample period of time to assure severance occurring before the band passes from under the iron.

Although in the foregoing there have been shown and described but a few of the preferred embodiments of the invention, it is to be understood that further variation in details of construction and combination of parts may be resorted to without departing from the spirit and scope of the invention as claimed.

We claim:

1. The combination with means for supporting continuously travelling glass tubing, of a track arranged parallel to the direction of travel of the tubing, a carriage on said track having a chuck for seizing said tubing whereby the carriage travels therewith, means independent of the tubing for controlling the actuation of said chuck, means for disabling said chuck, means for returning said carriage to its initial position by driving power derived from said traveling tubing, and means associated with said carriage for locally heating said tubing in the vicinity of its point of seizure by said chuck while the carriage is travelling with said tubing.

2. The combination as claimed in claim 1, which includes a stationary chilling member positioned beyond the point of disablement of the chuck and having a glass-engaging surface of substantial length for continuous contact with the tubing whereby a thermal shock is imparted to the tubing at its locally heated area to effect severance of the tubing.

3. Apparatus for severing continuously travelling glass tubing, including a ring burner surrounding the tubing, means for connecting the burner in fixed relation to the tubing whereby the burner circumferentially locally heats a narrow band of the tubing at the point at which it is to be severed, equipment for periodically actuating said connecting means, means to disable said connecting means, means energized during movement of the burner with the tubing to return the burner to its starting point between the periods of actuation of said connecting means, and a stationary chilling member positioned beyond the point of disablement of said connecting means and having a glass-engaging surface of substantial length for continuous passive contact with the tubing whereby the narrow heated band is chilled to effect severance of the tubing.

4. The apparatus as claimed in claim 3, in which the equipment for actuating the connecting means includes a timing device for initiation of the actuation thereof.

5. The apparatus as claimed in claim 3, in which the equipment for actuating the connecting means is under control of the travelling tubing.

6. Apparatus for severing continuously travelling glass tubing rotating about its own axis, comprising an annular heater through which the tubing passes, a support for said heater comprising a wheeled carriage, a track for said carriage arranged parallel to the direction of travel

of the tubing, a device associated with said carriage for attaching it to the rotating travelling tubing so that the heater travels with the tubing and locally heats it along a transverse line thereabout, means to periodically actuate said attaching device, means to disable said attaching device, a second device associated with said carriage into which energy is stored during movement of the carriage with the tubing for restoration of the carriage to its initial position following disablement of said attaching device, and a stationary chilling member positioned beyond the point of disablement of said attaching device and having a glass-engaging surface of substantial length with which the tubing is continuously in passive contact whereby a thermal shock is imparted to the rotating tubing along a substantial portion of the heated line thereabout to effect severance of the tubing.

7. The apparatus as claimed in claim 6, in which the means to disable the attaching device is actuated by the carriage upon its movement with the tubing for a predetermined distance.

8. The apparatus as claimed in claim 6, in which the means to actuate the attaching device includes a unit under whose control said device is attached to the tubing and mechanism for periodically actuating said unit.

9. In combination with means for continuously drawing glass tubing, an annular heater through which the tubing passes, means for attaching the heater to the tubing so that the heater travels with the tubing and locally heats it along a transverse line thereabout, means to periodically actuate said attaching means, said actuating means being operably controlled by the tube-drawing means, means associated with said actuating means to vary the periodicity of initiating

actuation of said attaching means, means to disable said attaching means, means energized during movement of the heater with the tubing for restoration of the heater to its initial position following disablement of said attaching means, and a stationary chilling member positioned beyond the point of disablement of said attaching means and having a glass-engaging surface of substantial length with which the tubing is continuously in passive contact whereby a thermal shock is imparted to the tubing along the heated line thereabout to effect severance of the tubing.
